UNITED STATES PATENT OFFICE.

FLOYD N. PRICE, OF FAYETTEVILLE, ARKANSAS.

ADJUSTABLE CUFF.

1,315,036.

Specification of Letters Patent.

Patented Sept. 2, 1919.

Application filed April 5, 1918. Serial No. 226,895.

To all whom it may concern:

Be it known that I, FLOYD N. PRICE, a citizen of the United States, residing at Fayetteville, in the county of Washington and State of Arkansas, have invented certain new and useful Improvements in Adjustable Cuffs; and I do hereby declare the following to be a full, clear, and exact description of the invention, such as will enable others skilled in the art to which it appertains to make and use the same.

The object of the invention is to provide, particularly for use in connection with dress or outer shirts for men, and shirtwaists and blouses for women and children, a double reversible cuff construction having a plurality of interchangeably usable cuff elements, either of which may be exposed, without detachment from the shirt sleeve and each of which is adapted to form a satisfactory finish for the sleeve, each cuff element being of the double or folded type now in practically universal use.

A further object of the invention is to provide a device of the type indicated whereby in its reversed positions the cuff member effects an adjustment of the length of the active portion of the sleeve, as by projecting to a greater or less extent and thus forming a longer or shorter sleeve and cuff combined.

A further and supplemental object of the invention is to provide a cuff construction such that one or the other of the elements may be exposed, when one becomes soiled, and whereby the durability or length of life of the garment is protracted by providing a double wearing surface for the exposed edge of the cuff portion, it being the universal experience, that a cuff, particularly of the doubled or folded type wears at the edge represented by the fold line between the inner and outer portions of the cuff.

Further objects and advantages of the invention will appear hereinafter, it being understood that changes may be resorted to within the scope of the claims without departing from the spirit thereof.

In the drawing:

50 Figure 1 is a perspective view of a cuff and attached portion of a sleeve such as that ordinarily employed in connection with men's shirts, one adjustment of the cuff member being shown.

55 Fig. 2 is a similar view showing the other adjustment of the cuff member.

Fig. 3 is a sectional view of the cuff member and the adjacent portion of the sleeve of the garment.

Attached to a sleeve 10 having the usual gap or placket 11, which may be provided with any suitable auxiliary fastening means such as a button 12 and button hole 13, is a cuff member 14 embodying the invention, said cuff member being connected with the extremity of the sleeve of the garment at an intermediate portion of the width of said cuff member, or on a folding or tilting line which is parallel with the opposite edges of said cuff member. The cuff member which as shown in Figs. 1 and 2 may be arranged in reversed positions, consists of a cuff element 15 extending in one direction from said line of attachment to or connection with the sleeve end, and an element 16, also of folded or doubled construction, extending in the opposite direction from said line of attachment to the sleeve, the element 15 being adapted to occupy a position within the end of the sleeve when the element 16 is adjusted for exposure, while the element 16 is adapted to lie on the outside of the shirt sleeve when the element 15 is adjusted for exposure. Preferably the edge portion of the fold or exposed portion 15^a of the element 15 is attached to the body portion of the cuff member and also to the sleeve, while the edge of the fold 16^a of the element 16 is free and occupies a position, when said element 16 is in use, which corresponds with that of the ordinary folded cuff now in common use. When the cuff is reversed however as shown in Fig. 2, to expose the element 15, the surface of the body portion of the cuff member is exposed and presents a doubled thickness 95 of cuff throughout. In order to arrange either of these cuff elements in operative position, it is only necessary to loosen the fastening devices, as by removing the cuff buttons, and tilt the cuff member upon the fulcrum formed by the line of attachment with the garment sleeve which line of attachment as above mentioned is located at an intermediate point between the fold lines 15^b and 16^b representing the cuff edges in the operative positions respectively of the elements 15 and 16, and therefore if the cuff has been worn in the position indicated in Fig. 1, with the cuff element 16 exposed, it is only necessary to reverse the position of the member 14 in order to bring the other cuff element into operative position and thus pre-

sent a clean cuff edge for view. Also obviously the reverse of the above described adjustment is attended by the same advantages.

It is sometimes desirable to provide for a variation in the length of the active portion of a sleeve, as for example to adapt a shirt of a given size or measurement to wearers having different lengths of arms, or to wearers having different taste as to the length 10 of the sleeve of the shirt, that is as to whether the edge of the cuff shall show beyond the coat sleeve or not, and it is also at times desirable to provide for an exposure 15 slightly of the cuff when a coat is worn, while preferable to have a shorter sleeve when the coat is removed, as in office work, where the sleeve is thereby held out of the way of the wearer in writing and handling papers and so forth, and to secure this further advantage, the line of attachment or 20 connection of the cuff member to the sleeve may be arranged at a point nearer one edge of the blank forming the cuff than the other edge, so that for example the cuff element 15 is short or narrow, while the cuff element 16 is long or broad as shown in the drawing. 25 Obviously with this arrangement, when the cuff element 16 is exposed as shown in Fig. 1 a longer active portion of the sleeve is provided, as for example when the coat is worn so as to show a portion of the cuff element 16, whereas when the position of the cuff member is reversed as shown in Fig. 2, the shorter element 15 is exposed, and the difference 30 in the length of the active portion of the sleeve will depend upon the position of the line of attachment with reference to the edges of the cuff and cuff blank for adjustment respectively of said cuff element. It 35 will be seen moreover that in the different adjustments of the cuff member, different portions of the surface of the member are exposed and when one cuff element is exposed, or arranged in operative position, the 40 portion of the surface which was exposed 45 when the other cuff element was in use, is now concealed, so that in the event that one cuff element has become soiled in use, the

exposure of the other cuff element will place such soiled portion where it will not be 50 visible.

The sleeve is provided with button holes 17 which align with button holes 18 of the cuff when the shorter portion of the cuff is extended thereby permitting a cuff button to 55 be extended through the alining openings to secure the ends together when the shorter portion of the cuff is extended. The single set of button holes 18 are disposed centrally of the longitudinal edges of the cuff thereby rendering the cuff button openings usable when either portion of the cuff is extended. 60

Having thus described the invention what is claimed is:

1. The combination with a sleeve, and a 65 cuff secured thereto at a point spaced from its longitudinal center thereby providing relatively long and short portions, said cuff having a single set of button holes centrally of its longitudinal edges, said sleeve having 70 button holes alining with the button holes of said cuff when the short portion of the cuff is extended, the button holes of said cuff being adapted for use when either portion of the cuff is extended. 75

2. The combination with a sleeve, of a cuff secured thereto at a point spaced from its longitudinal center thereby providing relatively long and short portions, folds secured to the longitudinal edges of said cuff, said 80 cuff and the folds of the relatively long portion having button holes disposed centrally of the longitudinal edges of the cuff, said sleeve having button holes alining with the button holes of said fold and said cuff when 85 the shorter portion of the cuff is extended, the button holes of said cuff being adapted for use when either portion of the cuff is extended.

In testimony whereof I affix my signature 90 in presence of two witnesses.

FLOYD N. PRICE.
